CLAIM

The ornamental design for a flat sided flashlight stun gun, as shown and described.

DESCRIPTION

FIG. 1 is a top perspective view of a flat sided flashlight stun gun showing my new design;

FIG. 2 is a right side elevational view thereof;

FIG. 3 is a left side elevational view thereof;

FIG. 4 is a front view thereof;

FIG. 5 is a rear view thereof;

FIG. 6 is a top view thereof; and,

FIG. 7 is a bottom view thereof.

The broken lines in FIGS. 1-7 illustrate portions of the flat sided flashlight stun gun that form no part of the claimed design.

1 Claim, 6 Drawing Sheets(56)
